UNITED STATES PATENT OFFICE.

MARSHALL R. BROWN, OF BELLEFONTAINE, OHIO, ASSIGNOR OF ONE-HALF TO DOW AIKIN, OF BELLEFONTAINE, OHIO.

RAIL CONSTRUCTION.

1,091,281.

Specification of Letters Patent. Patented Mar. 24, 1914.

Application filed December 18, 1913. Serial No. 807,508.

To all whom it may concern:

Be it known that I, MARSHALL R. BROWN, a citizen of the United States, residing at Bellefontaine, in the county of Logan and 5 State of Ohio, have invented certain new and useful Improvements in Rail Constructions, of which the following is a specification.

Owing to the character and construction 10 of road beds which are predestined to be adopted in the future by reason of scarcity of the usual materials employed heretofore, and the compulsory equipment of rolling stock of metallic or rigid structures, it becomes necessary to secure some economical 15 means of providing for resiliency for the protection of said stock, the articles or passengers transported thereby, and the provision for such resiliency is the primary object of my invention which relates to improvements in rail constructions.

To the end of accomplishing the foregoing object, my invention comprehends the provision of a rail comprising two essential 25 elements, namely, a tread or ball portion and a base portion forming a chair which is adapted to receive the former and to provide a resilient seat therefor, said elements so cooperating in assembled position as to eliminate 30 the necessity of employing fish plates or, in the repairing of worn tread surfaces, of withdrawing the fastening members for the rail from the ties on which it is disposed.

More specifically, the base portion or sub- 35 rail of my device consists of a sheet of metallic material pressed, rolled or bent so as to form an interlocking web portion for cooperation with the tread member and base flanges by means of which the rail is secured 40 upon the road bed or ties, said sheet also preferably comprising a tie engaging flange or bead for preventing the spreading of rails.

With these and further objects in view, as 45 will in part hereinafter be set forth and in part become apparent, the invention comprises certain novel constructions, combinations and arrangements of parts, as herein specified and claimed.

50 In the accompanying drawings, Figure 1 is a fragmentary perspective view of a rail constructed in accordance with my invention. Fig. 2 is a similar view showing a modification of the arrangement of parts.

55 Fig. 3 shows a fragmentary perspective view

of the sheet material from which the base section or portion of the rail is formed previous to bending of the same.

Throughout the following detail description, and on the several figures of the drawing, similar parts are referred to by like reference characters.

Specifically describing my rail, the same comprises the tread element or member A and the base member B. As hereinbefore mentioned the base member B consists of a sheet of metal, the under surface of which is formed with a narrow tie engaging flange or bead 1, the function of which will be hereinafter more fully set forth. The sheet B in the formation of a chair or base rail section to receive the tread member A is bent along its lateral portions back upon itself so as to form the horizontally extending base flanges 2 extending oppositely, and these base flanges are suitably provided with openings 3 through which spikes may be driven to fasten the rail upon its bed or ties. The longitudinal edges of the sheet metal are bent at angles to the base flanges 2 in an upward direction to form the web portion which is designated in the drawing by the characters 4-4'. In the preferred embodiment of the rail construction this web portion is formed so that the edges 4-4' are disposed in spaced relation to each other to receive the web portion 5 formed on the tread member A. Openings 6 are provided through the web portion of the base member

B in which suitable fastening members, such as rivets, bolts or the like, (not shown) may be passed to interlockingly secure the tread member A in its proper position on the base member B. The openings 6 are preferably elongated slots so as to accommodate relative expansion and contraction of the rail members in actual use of the same. It is to be noted also that in the preferred construction shown in Fig. 1, the sheet metal is formed with a longitudinally extending groove 7 at approximately its central line and on the upper surface opposite the tie engaging flange or bead 1 and in the assembling of the rail members, the web 5 of the tread member extends into this groove. The bearing of the tread member, however, is essential on the upper extremities of the lateral edge portions 4-4' of the web of the base member B, and this arrangement insures a resilient seat for the tread member A.

100 105 110

by reason of the bending of the base member as hereinbefore described.

In Fig. 1 it is to be noted that the side portion of the base member B designated 5 4' is wider than the side portion 4 and the longitudinal edge of the side portion 4' is bent at an angle or laterally so as to form a lip or flange 8. On the side of the tread member A corresponding to the flange 8, 10 said tread member is also formed with an offstanding lip or flange 9 which is adapted in assembling the parts to rest upon the lip 8, both of said lips 8 and 9 being provided with openings such as 10 to accommodate 15 fastening members for securing the member A to the base member B.

In the usual rail construction most of the lateral stresses against the rail are borne by the base flanges corresponding to the 20 flanges 2 of the present invention, but it will be evident to those skilled in the art to which this invention refers that the arrangement hereinbefore described assures the distribution of the stresses against the

25 tread member A to the web portion of the rail which by reason of the formation of the coöperating flanges 8 and 9 adequately reinforce the rail construction to withstand such stresses.

30 The relative length of the rail members A and B may be approximately the same, but it is preferable that they be arranged in the laying of the rail so that the ends of two tread members will meet substantially in the middle of a coöperating base member, thus making the joints of the tread members strong and smooth, as well as relatively rigid, preventing the wearing of the ends of the tread surfaces as is usual in the 40 ordinary construction of rails now employed. This arrangement, furthermore, dispenses with the necessity for fish plates or other devices for securing the rails together. The tie engaging flange or bead 1 of the 45 base member in laying of the rail is engaged with the tie and by reason of the interlocking disposition mentioned, spreading of the rails will be effectually prevented by reason of the coöperation of this bead and 50 the fastening members which pass through the openings 3 in the base flanges 2.

One of the economical advantages which is inherent to the rail construction described hereinbefore as my invention is due to the 55 fact that when the tread surfaces of the track have become worn by constant use it is only necessary to replace the tread A in its chair or base member B and this repair may be accomplished without withdrawing 60 the fastening members for the base portion which would result in the necessity of the formation of new holes in the ties to insure proper securing of the rail as is necessary in the replacement of a rail such as is now 65 in common use.

In Fig. 2 I have shown a slightly modified arrangement of rail construction in which the base member B' is formed with the bead 1' while the side portions of the sheet metal are bent to form the horizontal flanges 70 2' and the lateral edges thereof are bent upwardly to form the web portion 4', these edge portions being of equal length and disposed in contiguous relation to each other so as to extend upwardly between the web portions of the tread member A' which web is formed by the spaced elements 5'—5'. The same inherent resilient action is procured by this formation of the rail as is incident to the formation in the preferred 75 80 embodiment.

Other slight changes in the details of construction of the parts of which the rail of my invention consists may be made without departing from the spirit of the invention and within the scope of the claims here-to appended.

Having thus described my invention, what I claim as new is:

1. A rail of the class described comprising a tread member, and a base member comprising a sheet of metallic material bent to form a resilient receptacle for said tread member.

2. A rail of the class described comprising a tread member, and a base member comprising a sheet of metallic material bent to form a receptacle for said tread member and having a tie engaging flange formed thereon whereby to prevent lateral movement of the rail.

3. A rail of the class described comprising a tread member, and a base member comprising a sheet of metallic material bent so as to form a web portion for interlocking engagement with the tread member.

4. A rail of the class described comprising a tread member, and a base member comprising a sheet of metallic material bent back upon itself so as to form a base flange and a web portion adapted for interlocking engagement with the tread member.

5. A rail of the class described comprising a tread member, and a base member comprising a sheet of metallic material, the longitudinal edges of which are bent back upon themselves so as to form resilient base flanges upon which the tread member is seated.

6. A rail of the class described comprising a tread member, and a base member comprising a sheet of metallic material, bent back upon itself at each side to form horizontal oppositely extending base flanges, the edge portions of said material being bent at an angle to the flanges to form an up-standing web portion adapted for interlocking engagement with the tread member.

7. A rail of the class described comprising a tread member, and a base member

comprising a sheet of metallic material bent back upon itself to form resilient base flanges, the edge portions being bent upwardly to form a web portion, and one of said edge portions being bent again laterally to form a lip adapted to act as a seat for the tread member.

8. A rail comprising a tread member formed with an offstanding flange, and a base member of sheet metal bent to form a receptacle with which said flange co-operates for interlocking engagement.

9. A rail comprising a tread member formed with a web portion and an offstanding flange, and a base member of sheet metal

bent back upon itself from opposite sides to form horizontal base flanges, said sides being again bent at angles to the base flanges to form a web portion, one of said sides being again bent laterally to form an offstanding flange upon which the offstanding flange of the tread member is adapted to be seated, said base member having a tie engaging bead formed therebeneath.

In testimony whereof I affix my signature in presence of two witnesses.

MARSHALL R. BROWN.
